(57) **CLAIM**

The ornamental design for a frame for electric power assisted bicycle, as shown and described.

DESCRIPTION

FIG. 1 is a front and left side perspective view of a frame for electric power assisted bicycle showing my new design; FIG. 2 is a rear and right side perspective view thereof; FIG. 3 is a left side elevation view thereof; FIG. 4 is a right side elevation view thereof; FIG. 5 is a front elevation view thereof; FIG. 6 is a rear elevation view thereof; FIG. 7 is a top plan view thereof; FIG. 8 is a bottom plan view thereof; FIG. 9 is an enlarged and partial left side elevation view thereof, in which the area of enlargement is indicated between lines 9-9 in FIG. 3; FIG. 10 is a cross-sectional view thereof along line 10-10 in FIG. 9; FIG. 11 is a cross-sectional view thereof along line 11-11 in FIG. 9; and, FIG. 12 is a cross-sectional view thereof along line 12-12 in FIG. 9. The broken lines in the drawings illustrate environmental material that forms no part of the claimed design.
